UNITED STATES PATENT OFFICE

JOHN V. PALMER, OF PITTSBURGH, PENNSYLVANIA, ASSIGNOR OF ONE-THIRD TO HARRY I. NEAMAN AND ONE-THIRD TO JAMES M. MAGEE, BOTH OF PITTSBURGH, PENNSYLVANIA

CONNECTER FOR RAILWAY RAILS

Application filed January 30, 1930. Serial No. 424,623.

The general object which I have in view is the provision of new and improved means for connecting the adjacent ends of rails.

For this purpose I have invented a connector which in its preferred embodiment comprises fish plates which bridge the rail joint and are provided on their outer faces with abutments, clamping blocks also bridging the joint and arranged to be bolted up against the fish plates, said blocks being provided with recesses to receive the abutments and also provided with lower portions which are recessed to receive the base flanges of the rail and which extend under the latter, and through-bolts extending beneath the rail and clamping said blocks together.

In the preferred form of my invention I also provide a chair plate which supports the base of the rail ends from beneath and has its ends supported in seats in the clamping blocks, means being also provided, preferably the through-bolts for securing the chair rigidly in place.

Again, the abutments on the fish plates may be omitted together with the recesses in the clamping blocks.

Again, the fish plates may be omitted and the clamping blocks made to bear directly on the webs of the rails.

Other novel features of construction, and also of arrangement of parts will appear from the following description.

In the accompanying drawings, wherein I have illustrated a practical embodiment of the principles of my invention, Fig. 1 is a perspective view showing two rail ends connected in accordance with my present invention.

Fig. 2 is a sectional view taken along the line 2-2 in Fig. 1.

Fig. 3 is an inside elevation of one of the clamping blocks.

Fig. 4 is a perspective of one of the fish plates.

Fig. 5 is a perspective of the chair plate.

Figs. 6 and 7 are views similar to Fig. 2 but showing modifications.

Referring first to Figs. 1 to 5 of the draw-

ings, 1 and 2 represent a pair of aligned rails whose adjacent ends are to be connected.

3 represents the fish plates which are positioned at either side against the webs of the rails and which bridge the joint in the usual manner.

The fish plates are provided with the usual bolt holes to register with the bolt holes in the rails, and the outer of the said holes receive the usual bolts 4 which extend also through the holes in the rail.

The intermediate portions of the fish plates 3 are provided exteriorly with the abutments 5 which are preferably of rectangular shape and are elongated horizontally and bridge the rail joint. The bases of said abutments rest upon the base flanges of the rails. The abutments are preferably integral with the fish plates but may, if so desired, be rigidly attached to the fish plates as by welding.

6 represents the two clamping blocks, one for each side and which also bridge the rail joint.

The upper portions of the blocks 6 fit snugly against the fish plates 3 and have their inner faces recessed, as at 7, to receive and fit over the abutments. The lower portions of the blocks are recessed, as at 8, to receive and fit over the base flanges of the rail, the blocks extending beneath said flanges for the support.

The bolts 9 extend through holes in the rails, the holes 10 in the fish plates and the holes 11 in the clamping blocks.

The outer portions 10^a of the holes 10 of the fish plates are half-round, being cut in the top of the abutments 5, while the inner portions 11^a of the holes 11 in the blocks 6 are also half-round, being cut in the top wall of the recess 7, the half-rounds 10^a and 11^a mating to form complete holes.

The lower portions of the clamping blocks 6 are also provided with bolt holes 12 to receive the through-bolts 13 which extend beneath the bases of the rails at either side of the joint and clamp the blocks 6 together.

14 represents a chair plate positioned beneath the rail ends and bridging the joint to support the rails from below. The ends

of the plate 14 are supported by the clamping blocks 6. Thus the blocks may be provided with horizontally elongated holes or seats 15 to receive the ends of the chair plate.

5 Suitable means are provided to hold the chair plate rigidly in place. Thus I may and prefer to use the through-bolts 13 for this purpose, forming the bolt holes 12 in the blocks 6 as half-rounds cut in the bottom 10 wall or floor of the seats 15, said holes being completed by half-rounds cut or formed in the bottom surfaces of the chair plate 14.

In Fig. 6 I show the use of my bearing blocks and chair plate in connection with 15 the ordinary fish plates, the same not being provided with abutments as shown in the preceding figures, and the clamping blocks being of course provided with recesses to receive the abutments. Thus my invention may be applied to any rail joint 20 without changing the fish plates, longer bolts being inserted through the intermediate holes in the fish plates and the end holes in the rails to clamp the bearing 25 blocks in place.

In Fig. 7 I show the use of my bearing blocks without fish plates, the clamping blocks being formed to bear directly against the rail webs and bridging the joint.

30 It is evident that with the parts of my improved connector in position and the nuts on the bolts tightened and locked in the usual manner, the rail ends are securely connected together and supported against 35 undue flexing.

My improved connector is inexpensive to manufacture, and contains no parts which are subject to undue wear or breakage.

My improved connector may be quickly 40 applied and removed, and requires no alteration in the structure of the rails or of the track.

While for the sake of illustration I have shown my improved connector in connection 45 with the rails of the T-type used in steam railway practice, it is apparent that my invention may be likewise used in connection with girder rails and other types and shapes.

50 What I desire to claim is:—

1. A connector for rail ends comprising a pair of fish plates bridging the rail joint and fitting against the webs of the rails, abutments on the outer faces of said fish 55 plates and bridging the joint, a clamping block fitting against each of the fish plates and bridging the joint, said blocks being recessed to receive the abutments and to receive the base flanges of the rails, clamping 60 bolts extending through the rails, the fish plates and the clamping blocks, and through-bolts extending beneath the rails at either side of the joint and clamping the blocks together.

65 2. A connector for rail ends comprising a

pair of fish plates bridging the rail joint and fitting against the webs of the rails, abutments on the outer faces of said fish plates and bridging the joint, a clamping block fitting against each of the fish plates 70 and bridging the joint, said blocks being recessed to receive the abutments and to receive the base flanges of the rails, clamping bolts extending through the rails, the fish plates and the clamping blocks, and a chair plate supporting the rail ends from below and having its ends supported by the clamping blocks.

3. A connector for rail ends comprising 80 a pair of fish plates bridging the rail joint and fitting against the webs of the rails, abutments on the outer faces of said fish plates and bridging the joint, a clamping block fitting against each of the fish plates and bridging the joint, said blocks being 85 recessed to receive the abutments and to receive the base flanges of the rails, clamping bolts extending through the rails, the fish plates and the clamping blocks, a chair plate supporting the rail ends from below 90 and having its ends supported by the clamping blocks, and means for securing the chair plate to the clamping blocks.

4. A connector for rail ends comprising 95 a pair of fish plates bridging the rail joint and fitting against the webs of the rails, abutments on the outer faces of said fish plates and bridging the joint, a clamping block fitting against each of the fish plates and bridging the joint, said blocks being recessed to receive the abutments and to receive the base flanges of the rails, clamping 100 bolts extending through the rails, the fish plates and the clamping blocks, a chair plate supporting the rail ends from below and having its ends supported by the clamping blocks, and through-bolts extending beneath the rails and clamping said blocks together.

5. A connector for rail ends comprising 110 a pair of fish plates bridging the rail joint and fitting against the webs of the rails, abutments on the outer faces of said fish plates and bridging the joint, a clamping block fitting against each of the fish plates and bridging the joint, said blocks being recessed to receive the abutments and to receive the base flanges of the rails, clamping 115 bolts extending through the rails, the fish plates and the clamping blocks, a chair plate supporting the rail ends from below and having its ends supported by the clamping blocks, and through-bolts engaging said clamping blocks and said chair plate.

Signed at Pittsburgh, Pa., this 27th day of January, 1930.

JOHN V. PALMER.
